UNITED STATES PATENT OFFICE.

OLAF STROM, OF BROOKLYN, NEW YORK, ASSIGNOR OF ONE-HALF TO
OCTAVIUS E. NELSON, OF SAME PLACE.

DESIGN FOR A MATCH-STAND.

SPECIFICATION forming part of Design No. 21,511, dated May 3, 1892.

Application filed December 9, 1891. Serial No. 414,519. Term of patent 3½ years.

To all whom it may concern:

Be it known that I, OLAF STROM, a citizen of the United States, residing in Brooklyn, in the county of Kings, in the State of New York, 5 have invented and produced a new and original Design for a Match-Stand, of which the following is a specification.

My design is wrought out in the form of a statuette, representing the thin and pleasant-faced conventional Jonathan in costume holding his hat inverted in a deferential and inviting position in his hand.

The accompanying drawing forms a part of this specification and shows my design in front view.

My design consists in the Jonathan holding his hat in his hand in an inverted position.

Referring to the figure and the letters of reference marked thereon, A is the body of a statuette, A' the smiling face, and A² an arm and hand holding the hat B. A base C forms an ample support for the whole.

What I claim is—

The design for a match-stand or similar article, consisting of a Brother Jonathan with his hat in his hand inverted, as herein shown and described.

In testimony that I claim the invention above set forth I affix my signature in presence of two witnesses.

OLAF STROM.

Witnesses:

WILLIAM H. SMITH,
HENRY R. SUYDAM.
